UNITED STATES PATENT OFFICE.

LOUIS V. ARONSON, OF NEWARK, NEW JERSEY.

COMBINATION LOCK.

Application filed November 20, 1924. Serial No. 751,157.

To all whom it may concern:

Be it known that I, LOUIS V. ARONSON, citizen of the United States, residing at Newark, in the county of Essex and State 5 of New Jersey, have invented certain new and useful Improvements in Combination Locks, of which the following is a specification.

The invention relates to combination 10 locks and has as its object the provision of a lock of great simplicity, and which may be manufactured cheaply so as to make possible its use with a toy.

A further object of the invention is the 15 provision of an exceedingly simple combination lock which shall function accurately.

A further object of the invention is the provision of a combination lock which may 20 be made substantially throughout of metal stampings.

A further object of the invention is the provision of a combination lock wherein the 25 permutation elements are mounted upon the bolt to slide therewith.

Further objects of the invention will appear from the following description when read in connection with the accompanying drawings, wherein

30 Fig. 1 is a front elevation;

Fig. 2 is a central vertical section on line 2—2 of Fig. 1;

Fig. 3 is a vertical section on line 3—3 of Fig. 2; and

35 Fig. 4 is a rear elevation with the lock cover removed.

As shown, the lock is applied to a receptacle having an outer wall 10 and a circular end wall 11, in which a door 12, carrying 40 the lock embodying the invention, is hinged upon a pintle 13.

As shown, the lock comprises a dial 14 carrying a flat knob 15 integral therewith, and rigidly secured to a pin 16 passing 45 through the door, through the bolt 17, and having mounted thereon the permutation elements 18—19.

The element 18 is rigidly secured to the 50 pin 16, and the element 19 is loosely mounted thereon.

Annular rings 20—21 are shown rigidly secured to the permutation element 19 and freely movable on the pin 16. To cause 55 the picking up of the permutation element 19, when the permutation element 18 is revolved by the preparatory movement of the

dial 15, a notch 22 is provided in the ring 20, to co-act with a pawl 23 mounted upon a pin 24, carried by the permutation member 18. To press the pawl toward the ring 60 20, a spring 25 is shown mounted upon a pin 26 also carried by the permutation member 18.

The bolt 17, carrying the pin 16, the dial, and the permutation elements, is adapted to 65 slide on the door 12 so that the end 27 of the bolt escapes from its position in the rear of the wall 11 about the door opening. To permit of the sliding movement of the lock, the opening through which the pin 16 extends, is formed as a slot 28.

To prevent unauthorized movement of the bolt, a fence 29 is shown standing opposite 70 the edges of the permutation elements 18—19.

To permit the authorized movement of the bolt, a gate is shown in each of the permutation elements at 30—31. When the two gates are brought in registry at the same time with the fence 29, the bolt may be retracted and the door made free to open.

To bring the gates into registry the dial is turned in a preparatory direction, to the right, in the embodiment shown, the pawl 23 coming into contact with the notch 22 to 80 bring the gates into a predetermined relative position, and, by continued movement in the preparatory direction, to a position in which the correct number registers with the zero mark 32 on the door, the gate 90 30, in the permutation element 19 being brought opposite the fence 29.

By reversal of the movement of the dial, the permutation element 19 will remain in place and the gate of the element 18 will be 95 brought into registry with the gate 30 and to a position opposite the fence 29. If now the dial be moved bodily upon the door, the bolt will be retracted and the door permitted to open.

To hold the permutation element 19 from being moved by friction between the same and the permutation element 18, during the second setting of the dial, a spring 33, having two portions 34—35, which press against 105 the edge of the permutation element 19, is provided. The spring is shown as formed from a metal stamping, and the central portion has a flange 36 bent at an angle to the body of the spring and mounted upon the bolt 17 as by means of a rivet 37.

A cover 37' is shown for the mechanism

of the lock and may be secured to the door by tabs 38-39 passed through openings in the body of the door and clinched.

A retaining member 40 is also shown, 5 through which the bolt projects to take the strain of unauthorized attempts to open the door. The member 40 is shown as provided with projecting portions passing through the door and headed as at 41.

10 It will be seen that substantially the entire lock may be made up of metal stampings, and the assembly being very simple, the lock will be exceedingly cheap to produce as well as efficient in operation.

15 Minor changes may be made in the physical embodiment of the invention without departing from the spirit.

I claim:

1. A combination lock comprising, in combination, a bolt, a pin journaled in said bolt, a pair of permutation elements mounted upon said pin, one of said elements mounted for free revolution and the other thereof fixed to said pin, a pawl carried by said 25 fixed element, means carried by said free element to coact with said pawl upon revolution thereof in one direction, a spring mounted upon said bolt, having frictional engagement with said free element, said elements having gates adapted to be brought 30 into registry, and a stationary fence coacting with said gates.

2. A combination lock comprising, in combination, bolt having a pin journaled thereto in and adapted to slide therewith, a dial carried by said pin, a pair of permutation elements having gates, one of said elements

40 mounted upon said pin for free revolution with relation thereto, and the other thereof fixed upon said pin, a pawl carried by said fixed element, means carried by said free element to coact with said pawl to cause pick-up of the free element upon revolution of the dial in one direction, a spring carried by the bolt, having frictional engagement with a surface of the free element, and a stationary fence mounted adjacent said bolt to coact with said gates.

3. A combination lock comprising, in combination a door having a slot, a bolt mounted on said door for reciprocating movement, and having a pin journaled therein passing through said slot, a dial fixed on said pin upon the exterior of the door, a pair of permutation elements having gates 55 adapted to be brought into registry, one of said elements mounted upon said pin for free revolution with relation thereto, and the other thereof fixed to said pin, spacing elements rigidly mounted upon said free element, one of said spacing elements having a notch, a pawl mounted upon said fixed element to coact with said notch, to cause revolution of the free element when the dial is turned in one direction, a U-shaped spring 60 mounted at its central portion upon the bolt and frictionally engaging the edges of the free element between its ends, a fence fixed on the door adjacent said bolt whereby to prevent retraction of the bolt except when the gates are both brought into registry therewith.

LOUIS V. ARONSON.
